United States Patent

Des. 240,541
Patented July 13, 1976

240,541

CIGARETTE

John P. Rupert, Stellenbosch, Cape Province, Republic of South Africa, assignor to Tobacco Research and Development Institute Limited, Zug, Switzerland

Continuation of design application Ser. No. 252,958, May 12, 1972. This application Mar. 5, 1974, Ser. No. 448,232

Claims priority, application Republic of South Africa Mar. 14, 1972

Term of patent 14 years

Int. Cl. D27—01

U.S. Cl. D27—1

FIG. 1

FIG. 2

FIG. 3

FIG. 1 is a perspective view of a cigarette showing my new design;

FIG. 2 is an enlarged fragmentary side elevational view thereof; and

FIG. 3 is an enlarged fragmentary side elevational view showing a modified form of my new design.

The appearance of the end of the cigarette which is not visible in FIG. 1 is identical to the appearance of the end of the cigarette which is visible in FIG. 1.

I claim:

The ornamental design for a cigarette, as shown and described.
